UNITED STATES PATENT OFFICE.

JAMES E. GOODHUE, OF ST. CHARLES, ILLINOIS.

CORN-HUSKING MACHINE.

SPECIFICATION forming part of Letters Patent No. 739,540, dated September 22, 1903.

Application filed July 30, 1902. Serial No. 117,642. (No model.)

To all whom it may concern:

Be it known that I, JAMES E. GOODHUE, a citizen of the United States, residing at St. Charles, in the county of Kane and State of Illinois, have invented a new and useful Improvement in Corn-Husking Machines, of which the following is a specification.

My invention relates to corn-husking machines of the type shown and described in Letters Patent of the United States No. 683,174, granted to me September 24, 1901, which patent shows a machine employing yielding husk-loosening fingers supported in advance of the husk-removing mechanism to render more thorough the operation of the latter.

My present object is to provide certain improvements in and additions to the construction shown in my aforesaid patent with a view to increasing the capacity of the machine and making it more certain and positive in operation, and also with a view to obviating all danger of loss of corn-kernels which may fall from the ears during the husking operation, and, furthermore, to render the machine more perfect, economical, and desirable for its purpose.

Generally stated, my present machine operates as follows: The ear-carrying stalks when thrust into the machine are advanced through snapping-rollers which break off the ears and throw them upon husk-loosening mechanism, where the husks are loosened to facilitate their removal. The ears are discharged from the husk-loosening mechanism to husk-removing rollers which strip off the husks and silk, causing the ears with the kernels thereon to be discharged from one end of the machine. As the stalks pass beyond the snapping-rollers they are engaged by rotary cutting-knives and chopped into feed, the feed being discharged from the machine at the end thereof opposite that from which the ears are discharged. The husks and silk as they fall from the husking-rollers are moved along to mingle and be discharged with the chopped stalks. Any kernels of corn which may be loosened from the ears during the husking are separated from the husks and silk and discharged from another part of the machine.

Referring to the drawings, Figures 1 and

2 are broken views which, taken together, show the entire machine in side elevation; Fig. 3, a broken plan view of the lower or discharge end portion of the husk-removing mechanism, the view being taken from line 3 in Fig. 2; Fig. 4, a broken partly-sectional end view of the same, the section being taken on line 4 in Figs. 2 and 3; Fig. 5, a broken and enlarged central longitudinal section of a part of the machine, taken on line 5 in Fig. 11; Fig. 6, a longitudinal section of an end portion of the machine, the view being in the nature of an extension of the view shown in Fig. 5; Fig. 7, an enlarged broken section taken on line 7 in Fig. 5; Fig. 8, an enlarged broken section taken on line 8 in Fig. 1; Fig. 9, a broken elevation, on an enlarged scale, of the snapping-rollers; Fig. 10, a section taken on line 10 in Fig. 9; Fig. 11, a broken plan view of parts of the machine, the view being taken from line 11 in Fig. 5; Fig. 12, an enlarged broken plan view of the under side of one of the slats or finger-carrying sections of a traveling husk-loosening member; and Figs. 13 and 14, sections taken, respectively, on line 13 and 14 of Fig. 12.

A is the frame of the machine, consisting of uprights, beams, and braces constructed to suitably support the operating parts of the machine. Forming a part of the main frame is a bearing-platform B between more or less upright side boards B'. Supported beyond opposite ends of the platform B are shafts B² and B³, respectively, carrying sprocket-wheels B⁴, over which run endless chains B⁵, carrying an endless series of cross-slats B⁶. The platform B operates as a guide and bed across which the slatted apron B⁶ moves to feed the stalks to the snapping-rollers C D.

The peripheral faces of the snapping-rollers are formed, as shown most plainly in Figs. 9 and 10, with numerous recesses or cavities a, wide and comparatively deep at one end and tapering and becoming gradually more shallow toward the opposite end. The recesses are in parallel series around each roller, those of one series extending intermediate those of the adjacent-lying series, and each recess in the turning of the rollers registers with a companion recess on the other roller, whereby as they move toward each other they form gradually-closing pockets to receive and

engage stalks fed to them. The operation can be best understood by referring to Fig. 10. When the end of a stalk is thrust into the bite of the rollers, it will enter an open but gradually-closing pocket formed by companion recesses a and abut against the abrupt shoulders formed by the ends a' at the deep portions of the recesses. In the turning of the rollers the shallow ends a^2 of the recesses grip the stalks and squeeze them flat, thereby obtaining a powerful hold thereon, for the reason that the stalks swell into the pockets. In the movement of the stalks between the rollers they are engaged by the successive recessed portions, filling the pockets, so to speak, and insuring firm gripping and consequent forward feeding of the stalks. The rollers D C are upon shafts C' D', respectively journaled at opposite ends in upright journal-plates E, bolted to the main frame of the machine. Integral with the plates E is a housing E', extending across from side to side of the machine over the snapping-rollers, being shaped in cross-section as indicated most plainly in Fig. 5. On the inner sides of the plates E are ribs E ^{2} , forming guards which, as shown in Fig. 7, overlap the ends of the rollers and prevent material from crowding in between the ends of the rollers and the adjacent faces of the plates E. The bearings for the shaft D' are rendered yielding by springs D ^{2} in a common manner, so that the roller D may yield slightly with reference to the roller C. This construction being common, it is not thought necessary to illustrate it in detail. The shafts C' D' are provided at one side of the machine with intermeshing gears C ^{2} D ^{3} , and the shaft C' also carries a sprocket-wheel C ^{3} .

On the shaft C', at the opposite side of the machine from that shown in Fig. 1, is a gear-wheel C ^{4} and sprocket-wheel C ^{5} . (See Figs. 7 and 5.)

Just beyond the snapping-rollers and journaled in bearings on the main frame is a shaft F, which is the main drive-shaft of the machine. At one end it carries a drive-pulley F' (see Fig. 1) and adjacent thereto a small pulley F ^{2} . It also carries a pinion F ^{3} , which meshes with the gear-wheel C ^{4} . On the shaft F, between its bearings, is a rotary stalk-cutter G, having cutter-blades G', working past a stationary cutter-block G ^{2} , extending from side to side of the main frame adjacent to the snapping-roller C, as shown in Fig. 5.

At the lower forward side of the snapping-roller C is a forward-inclined deflecting-plate b, and at the under side of the cutter-block G ^{2} is a downward and backward extending deflecting-plate c, all as shown in Fig. 5.

Mounted in the frame just beneath the delivery end of the traveling feed platform or apron B ^{6} is a plate or support H, forming, with the yielding spring-fingers H' thereon, the stationary member of the husk-loosening mechanism. The support H extends entirely across the machine and is fastened at elongated

openings H ^{3} in its ends with bolts or the like to the side frames of the machine. It inclines forward, as shown, and is provided at its rear end with a downward-extending deflecting lip or guard H ^{2} . The fingers H' may be in three rows, as shown in Fig. 5, each row consisting of fingers placed at the desired distance apart. The fingers have backward-projecting free end portions H ^{4} and are adapted to yield readily in the forward direction, by which is meant the direction toward the left in Fig. 5. The construction may be the same in the main as in my aforesaid Letters Patent, and the elongated openings H ^{3} allow for slight adjustment in the vertical plane.

Journalized in the frame in the positions shown are parallel crosswise-extending shafts I I', provided toward opposite ends with sprocket-wheels I ^{2} . Extending over the sprocket-wheels are endless sprocket-chains K, the links of which are provided, as shown in Fig. 12, with laterally-projecting attaching-flanges K', which project inward or toward each other from the chains. The chains carry an apron consisting of an endless series of alternate wood and metal slats K ^{2} K ^{3} , respectively fastened at their ends to the flanges K' of the links K. The wooden slats K ^{2} have tapering edges, as shown. The metal slats K ^{3} are formed, as shown in Figs. 12, 13, and 14, with the upper plate portions d and flanges d' d ^{2} on their under sides. At intervals along each slat K ^{3} are openings e through the plate d, extending from the flange d' to the flange d ^{2} and registering at the flange d ^{2} with a gradually-diminishing recess e', extending to the edge of the slat, as indicated in Fig. 13. L L are yielding fingers mounted in the slats K ^{3} . Each finger L is coiled between its ends about a stud f, extending from a head f', fastened by means of a bolt f ^{2} to the under side of the slat. One end of the finger is bent to rest in a recess f ^{3} in the block and be clamped thereby firmly in place. Between the ends, as aforesaid, the finger is curled several times around the stud f and passes thence through the adjacent opening e, as shown most plainly in Fig. 13. Each finger has a bent free end portion L' and may yield under pressure in the backward direction until it rests in the recess e', as shown by dotted lines in Fig. 13. The surfaces of the slats K ^{2} and K ^{3} form a practically continuous platform or apron and constitute, with the spring-fingers L, the movable member of the husk-loosening mechanism. Beneath the path of the upper side of the apron described is a bearing-platform g, suitably supported between the shafts I I' to hold the slats as they slide over it against downward yielding. The upper surface of the apron is shown to be inclined at an angle slightly less than the angle of inclination of the member H; but they may be parallel. It is simply necessary that they should be approximately parallel, and their relative adjustment may be changed to meet varying conditions by raising or low-

ering the part H on its supporting-bolts, this being rendered possible by the elongated slots H³.

5 M M' are pairs of companion husking-rollers of the same construction substantially as in my aforesaid former patent. The inner adjacent recessed rollers M' are journaled at opposite ends in stationary bearings h, and the outer companion smooth rollers are journaled at 10 opposite ends in laterally-sliding bearings h', inwardly pressed by the springs h². The spring-pressed sliding bearings may be the same at opposite ends of the rollers. At their 15 upper ends the rollers are provided with pinions i, the pinions of companion smooth and recessed rollers intermeshing, as shown in Fig. 11. On the shafts of the recessed rollers M', adjacent to the pinions i, are bevel-pinions i', meshing with the bevel-pinions i² 20 on the cross-shaft i³, carrying a belt-pulley i⁴ at one side of the machine. Mounted in the frame beneath the movable husk-loosening member is a guard-plate N, (see Figs. 5 and 11,) which extends over the gears i² i' i and 25 bearings h h' at that end, terminating at its forward edge beneath the forward end of the traveling apron. At opposite sides of the husking-rollers M M' are inclined boards k k, and between the rollers M' is a low partition-30 strip l, beveled on opposite sides to a point along the center, as shown. P is an endless conveyer comprising endless chains m at opposite sides, connected at intervals by conveyer bars or strips m'.

35 Extending beneath the husking-rollers from the end of the machine upward to a point beyond the upper ends of the rollers is an inclined platform R. The conveyer-chains at each side run over sprocket-wheels n on a 40 shaft n' beneath the bearings at the lower ends of the husking-rollers, thence upward across the platform R and to the opposite end of the machine, where they pass over sprocket-wheels p on a shaft p' at that end, 45 thence under idle pulleys q on the shaft q' at the base of the machine, as shown.

On the inner sides of the main frame beyond the upper end of the platform R are angular metal guide-strips r, extending nearly to the 50 rear end of the frame, all as shown most plainly in Figs. 5, 6, and 8. The strips r form longitudinal guideways r' for the edges of a reciprocating sifting device S. The sifting device consists of sides s, a base-plate s', and 55 a perforated plate s² the full width and length of the sifting device above the base s'.

Mounted on the frame in a plane below the guides r are stirrups t t, as shown most plainly in Figs. 1 and 8, and extending through and 60 beyond opposite sides of the sifting device beneath the perforated plates s² are supporting-bars s³, which extend into and slide in the guides formed by the stirrups t. At the upper end of the sifting device S is an outlet s⁴, 65 and at the lower end of the device is an inclined laterally-extending chute s⁵, extending past one side of the machine. Mounted in

the frame in the position shown is a shaft u, carrying a pulley u'. The shaft u is formed with a crank, as shown in Fig. 5, to which is 70 connected the pitman v, which is pivotally connected at v' to the under side of the sifting device S.

In the frame, between the upper and lower stretches of the conveyer P, is a fan-blower 75 frame or casing T, which discharges into the sifting device over the chute s⁵ and beneath the perforated plate s² in the direction of the outlet s⁴ at the upper end of the sifting device. In the casing T is a rotary fan-blower 80 T' on a shaft T², carrying a pulley T³, beyond the side of the frame. As before stated, the shaft F is the drive-shaft of the machine, the pulley F' thereon being belted to a suitable driving power. (Not shown.) An endless 85 belt X passes over the pulley F² on the shaft F, thence under the pulley u' on the shaft u, thence over an idle pulley w on a shaft w', journaled on the side of the frame, thence around the pulley i⁴ on the shaft i³, thence 90 under and around an idle pulley x on a shaft x', journaled on the side of the frame, all as shown in Fig. 1. At the opposite side of the machine the shaft F is geared, by means of its pinion F³, to the large gear-wheel C⁴ on 95 the shaft C'. An endless chain Y extends from the sprocket-pinion C³ on the shaft C' over a sprocket-wheel I³ on the shaft I, thence under an idle sprocket y, and thence around a sprocket-wheel B⁷ on the shaft B⁸. An 100 endless drive-chain Z extends around the sprocket-wheel C⁵ on the shaft C' and a sprocket-wheel p² on the shaft p', and the pulley T³ is driven by a belt T⁴ from the pulley w. Thus all moving parts of the machine are 105 driven at desired relative speeds.

In operation the stalks carrying the ears of corn are thrown upon the traveling feed platform or apron formed by the slats B⁶ and fed with their butt-ends forward in the direction 110 of the snapping-rollers C D. The stalks are engaged by the pockets of the snapping-rollers, as before described, and fed along. As they pass through the snapping-rollers the ears are engaged and snapped off and fall 115 through the opening between the deflectors b H². As the stalks pass beyond the snapping-rollers they are chopped into feed by the rotating cutter G, the feed falling and being directed by the deflector onto the perforated 120 sifting-plate s² toward the upper end thereof. The ears dropping between the deflectors b H² fall upon the traveling apron K² K³, where they are engaged by the backwardly-yielding spring husk-loosening fingers L. The deflector 125 or guard H² prevents the ears from passing beneath the same while in an upright position, compelling them to assume a horizontal position before moving forward. As the ears are moved they are engaged by the yielding fingers L H' on opposite sides, which penetrate the husks and silk and effect thorough loosening thereof while the ears are being rolled along under the action of the moving apron. 130

The object of the spring-fingers here shown is the same as in my aforesaid former patent—that is to say, to loosen the husks and silk without loosening the kernels of the ears.

5 The advantages of the present construction of the movable husk-loosening member over my former construction are that thereby a more positive and even distribution of the ears is effected and they are fed with great 10 uniformity to the husking-rollers. Thus all danger of the accumulation of ears beneath the snapping-rollers and their being fed in bunches to the husking-rollers is avoided. Furthermore, in the present construction the 15 feeding is effected across the full width of the traveling apron, which may be the full width between the side frames of the machine. In the movement of the ears between the husk-loosening members thorough loosening 20 of the husks and silk is effected, whereby as the ears drop to the husk-removing rollers M M' they are in condition to have their husks and silk engaged and thoroughly stripped off by the said rollers. The guard-plate N prevents 25 any dust portions of husks or silk or inadvertently-loosened kernels of corn from dropping into the gears at the upper ends of the husking-rollers. Hanging in the frame in the position shown in Fig. 2 is a swinging 30 plate V. Any ears of corn thrown forward by the traveling husk-loosening member will strike the plate V, which operates as a deflector, and be caused to drop upon the upper end portions of the husking-rollers.

35 While my improved husk-loosening fingers and husking-rollers will tend to reduce to the minimum any loosening effect upon the kernels of corn, it is impossible to prevent a material quantity of kernels from dropping from 40 the ears during the husk-loosening and husk-stripping operations. One of the objects of my present construction is to prevent loss of these kernels. As the husks and silk are stripped from the ears they pass downward 45 between the husking-rollers and are deposited upon the conveyer-platform R, being moved by the conveyer slats or bars m' upward along the said platform and thence over the perforated plate s² and discharged through 50 the outlet s⁴. A plate R' is fastened along its lower edge to the upper end of the platform R and passes loosely over the perforated plate s² to bridge across the space between the upper end of the platform R and 55 lower end of the perforated plate. Any kernels of corn loosened from the ears in the husk-loosening or husk-removing operations will pass between the rollers M M' and fall, with the husks and silk, upon the platform R 60 and be conveyed upward across the bridge-plate R' to the perforated plate s².

In the rotation of the crank-shaft u the sifting device S is reciprocated rapidly, and in its reciprocation its movement in the backward direction is more rapid than the movement of the conveyer-strips m'. This shaking action of the perforated plate causes any

70 kernels of grain that may be carried thereto by the conveyer to drop through upon the base s' and run out at the chute s⁵. The fan-blower T' sends a current of air through the sifting device beneath the plate s², which current is strong enough to drive any particles of dust, silk, husks, or the like out through the opening at s⁴; but the current is not strong 75 enough to drive the kernels of corn in the backward direction. As the feed is chopped up by the chopper G it falls and is deflected by the plate c to the sifting-plate s² and is 80 conveyed, with the husks and silk, to the discharge end of the machine. The feed falls upon the sifting-plate s² toward the discharge end of the machine at a point beyond that portion where the sifting of the kernels from the husks and silk takes place. Thus such 85 kernels will not be mixed with the feed at all. Any kernels of corn that may pass the snapping-rollers and be mixed with the feed will also be separated by the sifting device S and discharged through the chute s⁵. To 90 prevent particles of feed from being thrown out of the machine by the rotary chopper, I provide a hood E', which is hinged to the hood E' at E⁴, whereby it may be raised to give access to the chopper when desired. 95

My improved machine has great capacity and operates to clean the ears thoroughly of the husks and silk without loosening the kernels from the ears to any material extent. Any kernels that do become loosened and fall from the ears are cleaned from dust and discharged separately from the machine. 100

While I prefer to construct my improvements throughout as shown and described, they may be variously modified in the matter of details of construction without departing from the spirit of my invention as defined by the claims. 105

What I claim as new, and desire to secure by Letters Patent, is— 110

1. In a corn-husking machine, companion, oppositely-rotating snapping-rollers provided in their circumferential faces with cavities, each wide and deep at one end and gradually tapering and becoming shallower at the opposite end, the cavities in each roller registering with coincident cavities in the other roller as they approach the bite of the rollers, whereby they form the opposite concave sides of stalk-receiving and gradually-closing pockets, substantially as and for the purpose set forth. 115

2. In a corn-husking machine, the combination of means for loosening the husks preparatory to the subsequent removal thereof from the ears said means comprising a stationary series of husk engaging and loosening yielding fingers and a traveling endless apron carrying like fingers and adapted in its upper traverse to convey the ears, said stationary and movable fingers coöperating to loosen the husks, and husk-removing mechanism receiving the ears from said apron. 125 130

3. In a corn-husking machine, the combi-

nation of means for loosening the husks preparatory to the subsequent removal thereof from the ears said means comprising a stationary series of husk engaging and loosening yielding fingers, a traveling endless apron formed of a series of parallel slats and yielding fingers carried by the slats and coöperating with the stationary fingers in the upper traverse of the apron to effect the loosening of the husks, and husk-removing mechanism below and receiving the ears from said apron.

4. In a corn-husking machine, the combination of means for loosening the husks preparatory to the subsequent removal thereof from the ears said means comprising a stationary series of husk engaging and loosening yielding fingers, a traveling endless apron formed of a series of parallel slats alternately

plain and carrying yielding fingers, the movable and stationary fingers coöperating in the upper traverse of the apron to effect the loosening of the husks, and husk-removing rolls below and receiving the ears from said apron.

5. In a corn-husking machine, a husk-loosening member comprising a traveling apron formed with slats having series of openings, detachable blocks on the under sides of the slats provided with studs, and spring-fingers clamped at one end by said blocks, coiled between their ends around said studs and passing outward through said openings, substantially as and for the purpose set forth.

JAMES E. GOODHUE.

In presence of—

ALBERT D. BACCI,
L. HEISLAR.
